UNITED STATES PATENT OFFICE.

E. MCKINNEY, OF CLARKSVILLE, TENNESSEE.

IMPROVEMENT IN COAL-OIL STOVES.

Specification forming part of Letters Patent No. 58,862, dated October 16, 1866.

To all whom it may concern:

Be it known that I, E. MCKINNEY, of Clarksville, in the county of Montgomery and State of Tennessee, have invented a new and useful Improvement in the Application of Petroleum as a Fuel for Stoves, Furnaces, &c.; and I do hereby declare that the following is a full, clear, and exact description thereof, which will enable others skilled in the art to make and use the same, reference being had to the accompanying drawing, forming a part of this specification.

The drawing represents an elevation of a stove, partly in section, with my improvement applied to it.

This invention relates to a new and improved means of feeding or supplying petroleum to stoves, furnaces, &c., to serve as a fuel for the same.

The invention consists in the employment or use of water or other fluid having a greater specific gravity than the petroleum, and placing the former in an elevated tank or reservoir communicating with the lower part of the petroleum-chamber by means of a pipe, so that the petroleum will be fed to the fire pan or chamber by static pressure.

The accompanying drawing exhibits the invention applied to a stove; but substantially the same arrangement of parts is employed in all cases, so far as the mere feeding or supplying of the petroleum to the fire is concerned.

A represents the external cylinder or drum of a stove; B, the base thereof, and C the fire-pan, to which the petroleum is fed into a bed of sand or other substance, on the surface of which the petroleum is burned.

D represents the petroleum-chamber, placed in the lower part of the drum A, and communicating with the center of the pan C by a pipe, E, provided with a cock, F.

G is a pipe provided with a cock, H, leading from the petroleum-chamber.

I is an elevated tank or reservoir, which is at the outer side of the stove and above the fire-pan C, said tank or reservoir communicating by a pipe, J, with the bottom of the petroleum-chamber D. The space between the top of the chamber D and the fire-pan C is filled with water, in order to guard against explosions, the water keeping the petroleum in the chamber D in a cool state.

From the above description it will be seen that the petroleum will be fed up to the fire-pan C by static pressure, the superior gravity of the water or other liquid in I causing the petroleum to remain on the surface of the former, and admitting of the apparatus being quite portable, the oil itself, or other fluid as light, requiring a much more elevated reservoir.

The supply of the petroleum to the fire is regulated by the cock F.

Having thus described my invention, I claim as new and desire to secure by Letters Patent—

The feeding or supplying of petroleum to stoves or furnaces by means of water or other fluid of a greater specific gravity than the petroleum, placed in an elevated tank or reservoir above the petroleum-chamber, and communicating with the latter in such a manner as to feed the petroleum to the fire-pan or fire-chamber by static pressure, substantially as described.

E. MCKINNEY.
